United States Patent Office

Des. 225,719
Patented Jan. 2, 1973

225,719

BOTTLE

Darlene V. Bradrick and Janice P. Lehne, both of 6145 Bennington Drive, Newark, Calif. 94560

Filed Aug. 26, 1971, Ser. No. 175,427

Term of patent 14 years

Int. Cl. D9—01

U.S. Cl. D9—35

FIG.2

FIG. 1 is a front elevational view of a bottle showing our new design;

FIG. 2 is a left side view of FIG. 1; and

FIG. 3 is a back view of FIG. 1.

We claim:

The ornamental design for a bottle, substantially as shown.
